UNITED STATES PATENT OFFICE.

J. VINCENT RENCHARD, OF WINDSOR, ONTARIO, CANADA.

LUBRICATOR.

SPECIFICATION forming part of Letters Patent No. 273,158, dated February 27, 1883.

Application filed September 30, 1882. (No model.)

To all whom it may concern:

Be it known that I, J. VINCENT RENCHARD, a citizen of the United States, residing at Windsor, Province of Ontario, Canada, have invented an Improved Lubricator, of which the following is a specification.

This lubricator is designed to lubricate the valves and other internal mechanism of the steam or other engine or motors by employing a compression mechanism intervening between an admission-passage subjected to the pressure from the boiler or generator and an oil-discharge passage subjected to the variable pressure or vacuum from the steam-chest of an engine or other place of attachment.

The mechanism consists principally of two movable pistons which are caused to travel between the admission and discharge orifices by motion transmitted from any of the moving members of the engine, so that they shall, with a reciprocating movement, alternately communicate with the said passages by opening and closing them to prevent direct communication between the boiler and the engine pressures or vacuum, and to open and separate at the admission-orifice, so as to receive between their faces or ends a prescribed quantity of lubricant, according to the extent of travel imparted to them by the transmitting member of the engine, then return simultaneously, holding the pocketed lubricant intact and conveying the same until brought into communication with the discharge-orifice, and then have their faces brought into contact by means of stops and a tension-mechanism, so as to compress the lubricant, causing it to enter the discharge-passage, through which it passes to the parts to be lubricated. The quantity of lubricant entering between the faces or ends of said reciprocating pistons is to be forced therein by the steam and hydrostatic pressure from the boiler upon or under the lubricant, and conveyed between the ends or faces of said pistons to a discharge-orifice, thus temporarily closing the admission-orifice, the discharge-orifice being similarly closed while the ends of said pistons are in communication with the admission-orifice.

Figure 1 is an end elevation of a locomotive-cylinder with my lubricator attached and properly connected. Fig. 2 is a side elevation of

a cylinder with the lubricator attached. Fig. 3 is a vertical central section of the lubricator shown in Figs. 1 and 2. Fig. 4 is a vertical central section of the lubricator in a plane at right angles to the one in Fig. 3. Fig. 5 is a horizontal section of the same on line W W in Fig. 4. Fig. 6 is also a horizontal section through the line X X, Figs. 3 and 4. Figs. 7, 8, 9, 10, and 11 are details from the drawings.

In the drawings, A is the oil-magazine; a', its fixed cover; a², the oil-filling plug; B, the steam-chest of a locomotive; b', the valve-stem; C, a portion of the locomotive-boiler; D, a two-way valve screwed into bottom of boiler.

E is a tube communicating between the boiler and the oil-magazine; e², a passage for admitting water from boiler to oil-magazine; e³, a valve for controlling said passage; e⁵, a valve for discharging or emptying substances from the oil-magazine, with conducting-tube e⁸ as the terminus or discharge-orifice; F, a steel arbor, a portion of which (indicated by dotted lines in Fig. 3) is squared. Said portion is also shown in Fig. 4 in cross-section. Its inner end is turned to the diameter of the sides of said square, so as to form a journal, which rests in the inwardly-projecting bearing f'. Through the opposite side of the oil-magazine, which also projects inwardly, is screwed a sleeve, f², which, with packing and nut f⁵, forms the other bearing for arbor F.

f³ is a fixed collet secured to arbor by a pin, f⁴, to prevent end motion.

f⁶ is an oscillating crank-arm secured to arbor F.

f⁸ is an adjustable journal-head held in adjustment by set-screw f⁹.

f¹⁰ is a connecting-rod uniting the valve-rod b' of locomotive with the oscillating crank-arm f⁶.

f¹¹ is a bracket fixed to valve-rod b' to communicate motion from the valve-rod to the connecting-rod f¹⁰.

G is a brass sleeve (shown in Fig. 9 detached) having a square hole through its entire length, and fitted to slip over the arbor F, as shown in Figs. 3 and 4. The outside of said sleeve contains two flutes, which are intended to prevent the tension-rings g², g⁴, and g⁶ from turning, said tension-rings being pro-

vided with centrally-projecting ears to correspond with the flutes in the sleeve G. Said sleeve is also provided with a screw-thread to receive the lock-nuts g^7 and g^8 , used to produce and hold the tension, as explained hereinafter.

g^4 and g^3 are cams or clutches located between the head of sleeve G and eared rings g^2 and g^4 .

g^5 is a spiral spring located on the sleeve G, between eared rings g^4 and g^6 .

It will be seen that a tension is formed against the cams or clutches g^4 and g^3 by means of the eared rings g^2 , g^4 , and g^6 , the spring g^5 , and the lock-nuts g^7 and g^8 . This tension mechanism is accessible, for the purpose of adjusting it, by removing the cover a' .

H is a stationary ring, cast in and forming a part of the oil-magazine A by means of a bridge extending from the ring proper to the opposite walls of the oil-magazine, plainly shown in Figs. 4 and 6. The ring is split, as shown, and provided with a compression-screw, h' . It is also provided with an oil-passage, h^2 , at the top and an oil-discharge passage, h^3 , at its bottom, to which is connected a conducting-tube, h^4 , and to close communication between the steam-chest and oil-magazine it is provided with a diaphragm, packing, and packing-nut, h^5 and h^6 .

J is a grooved ring with nearly half of the central periphery cut away. (See Figs. 11 and 4.) The grooved opening is intended to admit the projecting arms of the cams g^4 and g^3 . (See Fig. 4.)

j' and j^2 , Fig. 10, are two segmental piston-rings, which, when laid in a circle, as shown in Fig. 10, do not form a complete ring, having a segment removed. Near the ends of the portion left open are two lateral slots (see Fig. 4) to admit of engagement with the projecting arms of cams g^4 and g^3 . Said rings are turned to fit the groove in ring J precisely as the rings in an engine-piston are fitted. The rings being inserted in the groove of ring J, the combination is then inserted into the exterior or split ring, H, which latter is then compressed by the screw h' , making a tight joint on the periphery of ring J, while the segmental piston-rings j' and j^2 are sufficiently loose to admit of their movability by the projecting and engaging arms of the cams g^4 and g^3 , which latter are held temporarily fixed upon the sleeve G by the tension produced by eared rings g^2 , g^4 , and g^6 , spiral spring g^5 , and lock-nuts g^7 and g^8 .

It will be obvious that by the reciprocating motion of the engine's valve-rods an oscillating motion is imparted to the arbor F, and accordingly to the sleeve G and all the tension mechanism mounted thereon. Accordingly the oil-pocket between the faces or ends K of the piston-rings j' and j^2 is brought alternately in communication with inlet and discharge passages h^2 and h^3 .

As connected to the locomotive-engine, the lubricator is mainly attached or screwed into the steam-chest cover. (See Figs. 1 and 2.) It also communicates with the boiler or gener-

ator through the pipe E and two-way valve D. The pressure or vacuum from the steam-chests is against and into the discharge tube and passage h^4 and h^3 , while the pressure from the boiler is against and into the passage h^2 , and accordingly into oil-magazine. The piston-rings j' and j^2 only intervene between the boiler and steam-chest pressures.

The operation of the lubricator is as follows: 75 The valves e^4 and e^5 are opened and the magazine cleaned by being blown through when said valves are closed. Filler-plug a^2 is removed and the magazine A filled with lubricant. Filler-plug a^2 is then replaced, the valve b^3 is opened, 80 admitting pressure from the boiler through pipe E. The lubricator is now ready for use, and when the locomotive is brought into service it begins to operate in the following manner: Assuming the faces of the piston-rings 85 (marked K, Fig. 4) to be coincident to the discharge-orifice h^3 , the valve-rod of the locomotive transmitting an oscillating movement to the arbor F, the division between the faces K will remain closed, and the piston-rings 90 j' and j^2 will oscillate until the faces K become coincident with the inlet-passage h^2 , precisely as illustrated in Fig. 4. The lower ring, j' , ceases to travel because the arm of cam g^4 will have been brought into contact with 95 the remaining bridge N of the grooved ring J at a point marked L in Fig. 4, while the upper ring, j^2 , will continue to move according to the continued travel of the engine valve-rod, and thus separate from the lower ring, creating 100 between the two piston-faces a pocket or space, into which will rush the lubricant from the oil-magazine, imbued with the pressure from the boiler. The valve-rod of engine reciprocating will cause the two piston-rings to oscillate in 105 the opposite direction, the space containing the lubricant remaining intact until the face K of the lower ring becomes again coincident to the discharge-passage h^3 , when by means of a stop-pin, M, projecting slightly from the face 110 of the flange of grooved ring, Fig. 11, its further movement is arrested, while the continued motion of the upper ring, j^2 , brings the same into contact with the lower ring, j' , thus expelling by compression the lubricant contained 115 between the rings into the oil-discharge passage h^3 , through which it finds its way to the parts to be lubricated.

It will be seen, assuming the rings in the position illustrated in Fig. 4, that the division 120 K between the faces cannot travel any farther downward than to be opposite or coincident to the discharge-passage h^3 , because the lower ring at its upper end will have been stopped by the pin M. If, however, the arbor F continues to oscillate by the continued travel of engine valve-rod, the valve of the tension mechanism is again brought into use, as the arbor, sleeve, eared rings, spring, and nuts will continue their oscillation, rubbing the faces of the 125 cams while they remain stopped. In fact, the arbor and its mountings may be revolved with-

out resistance other than that created by the tension, as described, which can be adjusted to any required pressure. The movement of the piston-rings in the direction in which they come in communication with the discharge-passage h^3 is limited as to extremity of travel by pin M and subsequent contact of their faces K, while in the opposite direction the travel of the lower ring is limited by the bridge N at the point L, near upper ring, while the upper ring continues its movement, creating thereby a pocket or receptacle in extent proportioned to the travel of the engine valve-rod, but ultimately limited by coming in contact with the end of the lower ring.

The automechanically-regulated oil-pocket between the faces K of the piston-rings is governed by the extent of travel of the engine valve-rod and meets the exigencies of the engine, for when the locomotive is running at high speed—as with a light train—the driver “raises” the reversing-lever, and thus causes the valves to cut the steam off early in the stroke of the piston. This shortens the travel of the valve-rod of engine, and likewise limits the opening of the pocket or receptacle between the piston-rings, reducing the supply of lubricant. When the locomotive is laboring heavily or ascending a grade the driver naturally “drops” the reverse-lever, thus giving increased length of travel to the valve-rod, and accordingly the oil receptacle or pocket receives a greater opening. Consequently more lubricant is supplied to the engine. In the two latter conditions there is a variable pressure of steam within the engines, which, however, is more than balanced by the combined boiler and hydrostatic pressure within the oil-magazine. In case, however, the engine approaches a station or is running down a grade, the demand for lubricant is greatest, when the driver may drop his lever, giving the rods their fullest throw, and hence supply the engine with ample lubricant.

Should there be a slight tendency to leakage through the groove or channel of the piston-rings j' and j'' , the tendency given the discharging oil by the pressure within the oil-magazine and the absence of pressure, or the existence of a vacuum from the steam-chest of engine, will possibly and favorably augment the flow of lubricant, which is then most required.

The opening or separation of the piston-rings j' and j'' to suit the requirements of the engine regarding its proper supply of lubricant can be easily regulated by adjusting the journal-head f^o . When the latter is adjusted to give the required amount of lubricant under a high speed and regular work the supply for all extreme conditions of the locomotive's service will be further and correctly regulated automatically, as before explained.

On stationary and marine engines this lubricator may be differently employed. For instance, in place of being attached to the steam-

chest it may be attached to the steam-main, not only by its connecting end, but also by the pipe E, which may then be arranged to supply hydrostatic pressure by the steam, which will condense therein, and thus form the needed water, which is also used to take the place of the lubricant as it is expelled from the oil-magazine. If there is sufficient hydrostatic pressure to overcome the counteracting pressure into which the lubricant is compressed, the lubricator will be successfully operative.

On a locomotive-engine the pressure in the steam-chests may be considered as nearly dynamic in its action during violent laboring of the engine. Hence to overcome any possible resistance to a certain discharge of the oil I prefer to place the lubricator in such relative position to the boiler as to get the hydrostatic pressure from the same, added to the steam-pressure, to insure sufficient initial pressure upon the lubricant. The perhaps otherwise turbulent lubricant within the magazine is thereby tranquilized, and any susceptibility to follow the fluctuations within the engine through a possible leakage of the reciprocating mechanism averted.

The oil-magazine may be provided, as shown in the drawings, Fig. 3, with an indicator-tube, O, to illustrate the levels of the oil and water therein, and which may be attached to the oil-magazine in any of the ways known to the art.

On stationary and marine engines, to illustrate the rate of the feed of lubricant, an indicator may be located between the discharge-tube h^4 and the point of entry to the steam-main, and the discharging lubricant caused to pass visibly through the indicator in any of the ways known to the art.

I am familiar with the various patents in which hydrostatic pressure is employed to expel the lubricant and cause it to enter the steam, the oldest of which was granted to John Absterdam in 1854, and another granted to myself, jointly with John J. Renchard, November 14, 1876, reissued September 20, 1881. In this class of lubricators the hydrostatic pressure is employed to expel the lubricant by its superior force through apertures provided by stops or valves actuated by hand or automatically, as check-valves, the water under hydrostatic pressure entering the oil-magazine by an aperture, which, being opened and closed by the operator, accordingly regulates the outflowing lubricant. This class of lubricators are ill adapted to locomotive-engines, for the reason that the oil in the magazine is in direct communication with the variable pressure and vacuum from the steam-chests, and the lubricant being thus constantly agitated by the invading steam from the engine, its discharge cannot be regulated. It also becomes disintegrated, its lighter elements saponify, and by their expansion enter the engine in force, while the heavier elements, having limited expansive qualities, require to be supplied in larger quantity than a normal lubricant to give sufficient lubrication.

In my device, however, I supply the hydrostatic and steam pressure from the boiler upon the lubricant in the oil-magazine for the following reasons: First, the said pressure upon the oil practically excludes any steam or vapor from the engine into the oil through the movable mechanism by which the oil-pocket is formed; second, it prevents wear in the movable mechanism which constitutes the contractible oil-pocket by its tendency to surround the movable and contractible oil-pocket mechanism with a film of lubricant under a pressure in excess of that in the steam-chests of engine, and thus effectively balances said mechanism; third, it prevents the formation of oxides or incrustation of steam-disintegrated oil around the movable oil-pocket mechanism, which would be forced through any leakage in said mechanism by the steam-pressure from the engine, were it not that the hydrostatic and steam pressure exerted by its superior force a tendency for all substances to pass engine-ward, and thus add new oil to the wearing parts by expelling the old; fourth, the intervening reciprocating cut-off mechanism precludes any direct communication between the varying pressures upon the admission and discharge passages, the hydrostatic and the steam pressure is used to fill the pocket, automechanically formed between the ends of the piston-rings j' and j^2 , with lubricant, which remains imbued with that pressure until it is brought in communication with the discharge-orifice, into which it enters against the lesser opposing pressure by its own reserved force, as well as by the compression from contact of the face ends of the segmental piston-rings, which are closed automechanically, and which by their complete contact also prevent the invasion of any vapors or substances from the engine.

I am also familiar with that class of lubricators in which a piston moving in a cylinder is employed for expelling the lubricant, as that of William A. Clark, No. 201,332, March 19, 1878. In his device both ends of the cylinder are subjected to the pressure from the engine, thus holding the piston in equilibrium. One end of the cylinder contains the lubricant, the other steam or water. The piston is provided with an operating mechanism, and during its transit through the cylinder expels the contained lubricant. The latter is, however, continually subjected to the various pressures from the engine and its consistency accordingly varied, while in my device the lubricant remains tranquil or normal, and therefore free from heated vapors and disintegrating influences, and while the quantity of lubricant expelled by his device is dependent as well upon its condition as upon the movement of the piston, the quantity expelled by my device is automechanically measured and positively discharged without being subjected to the disturbing influences of fluctuating pressures from the engine.

Another class of lubricators which in their construction employ the well-known pump

mechanism, composed of a plunger, and receiving and retaining valves sufficiently minute to pump the required amount of lubricant suitable to every revolution of the engine, are unreliable, from the fact that the valves are subjected to choking or clogging by trifling impurities in the lubricant, and also in that the piston, when to its inmost limit, cannot expel all the lubricant which may have been taken into the pump "barrel" or cylinder, because a certain area is occupied to form seats for the valves, and thus when the plunger is withdrawn the remaining lubricant will expand (as it will have become elastic by heat or invading vapors from the discharge-passage) and fill the newly-made space, and thus prevent the admission of fresh lubricant; hence the incumbent lubricant is churned or agitated, rather than positively discharged into the engine, and if the pump is made large enough to insure the pumping and discharging of lubricant it will necessitate the use of reduction-gear in the way of ratchet mechanism to feed the lubricant in required quantity, and such mechanism involves complication and is therefore objectionable.

I am also aware that a contractible oil-pocket has been devised; but such contraction is entirely different from that which is described in my device. The purpose was not to regulate the discharge of lubricant to conform to every change or condition in the working of the engine, but rather to be able to reduce mechanically the size of a "measuring-cup," so that the average consumption of lubricant might be varied and not the immediate requirements of the engine be met. Also, the contractible oil-chamber shown in the patent to A. S. Harrison, March 2, 1880, No. 225,124, and the one in the modification of the Absterdam patent of 1854, November 21, No. 11,958, are for an entirely different purpose from that described in my invention. In neither of the latter can the contraction of the pocket prevent the invasion of steam or vapor into the oil-chamber from the discharge-orifice. In my device this is so by means of an oil-pocket, the walls of which are brought into contact with every revolution of the engine, and also by the tendency of the boiler-pressure through any leakage in the mechanism which forms the pocket no steam or vapor from the engine can back into the oil in the magazine and disintegrate or affect it in any way.

In my device shown in the drawings I employ a reciprocating mechanism composed principally of two segmental piston-rings, which may be very small in cross-section, which traverse simultaneously while in contact until their point of contact corresponds with the admission-passage, when by a tension mechanism one of the rings continues its movement, while the other remains stationary from contact with a stop for that purpose provided, thus making a gap or receptacle between their ends into which the oil, imbued by hydrostatic and steam pressure, is forced. The rings thus

separated then reciprocate and hold the imprisoned lubricant intact until their face ends communicate with a discharge-orifice, when they are brought again into contact, and thus 5 expel by compression the imprisoned lubricant without leaving any space to be subsequently filled by invading vapors or other substances.

I do not intend to limit or confine myself to the use of the segmental piston-rings alone for 10 forming an oil-pocket operating as above described, as I am aware that a number of different devices may be constructed to perform the same function. The spirit of my invention principally consists in forming an oil-pocket which 15 shall be automechanically moved from the receiving-inlet to the discharge-orifice, and to convey a desired quantity of oil and expel it forcibly therefrom without allowing the existing pressure upon the inlet and outlet ori- 20 fices to be in communication with each other. As I prefer, for the reasons above stated, to use the hydrostatic and steam pressure combined from the boiler, so as to imbue the lubricant with sufficient overbalancing force to 25 prevent any possible injurious reaction from the engine, I may in certain cases be obliged to forego the use of hydrostatic pressure, without which my device is, however, still satisfactorily operative.

30 Having thus fully described my invention, what I claim as new, and desire to secure by Letters Patent, is—

1. In lubricators, the method of injecting lubricants, consisting in a movable and contractible oil-pocket which becomes filled with lubricant when communicating with the inlet-orifice, and by its transit closes said orifice and conveys the pocketed lubricant to a discharge-orifice, into which it is expelled by the 40 closing or contraction of the pocket, substantially as and for the purpose specified.

2. In lubricators, and for the purpose of preventing steam or vapors from the engine from entering and mingling with the lubricant in the 45 oil-magazine, the contractible oil-pocket which closes when discharging its pocketed lubricant, substantially as specified.

3. In a lubricator, and as a means for forming an oil-pocket, two segmental piston-rings 50 inclosed in a grooved channel and leaving between their ends a contractible oil-pocket, substantially as described.

4. In a lubricator, and as a means for controlling the oil-pocket formed between two seg- 55 mental piston-rings, the cams g' and g'' , engaging with said piston-rings and imparting to them by proper devices a reciprocating motion, substantially as described.

5. In a lubricator, and as a means for ex- 60 pelling the lubricant from the oil-pocket, the piston-rings j' and j'' , cams g' and g'' , and stop-pin M , in combination with the tension device, substantially as and for the purpose described.

6. In a lubricator, and as a means for regulating the size of the oil-pocket, the piston-rings j' and j'' , cams g' and g'' , the tension device, grooved ring J , arbor F , adjustable crank-arm f^6 , and connecting-rod f^{10} , connecting with valve-rod b' , substantially as described. 65

7. In lubricators, and to enable the reciprocating or oscillating oil-pocket mechanism to be freely moved in its transit-space, and yet exclude any vapor or steam from the engine from entering the oil in the magazine through any leakage around said mechanism, the pipe 75 E , communicating between the boiler and the oil-magazine, whereby the steam and hydrostatic pressure from the boiler may be exerted against the lubricant in the oil-magazine, substantially as specified. 80

8. In lubricators, and to provide for the continued lubrication of the reciprocating or oscillating oil-pocket mechanism with new or fresh oil, to the exclusion of the old, the pipe E , communicating between the boiler and oil-magazine, whereby the steam and hydrostatic pressure may exert a superior force against the oil in the magazine, causing it to seek an outlet through and around any leakage in the reciprocating mechanism toward the engine, substantially as specified. 85

9. In a lubricator, and in combination therewith, the tension device herein described, consisting of sleeve G , eared rings g^2 , g^4 , and g^6 , spring g^5 , and lock-nuts g^7 and g^8 , substantially 90 as described.

10. In a lubricator, the automechanical device herein described for imparting a reciprocating motion to the piston-rings j' and j'' , consisting of the arbor F , fluted sleeve G , fitted 100 on the square portion thereof, cams g' and g'' , eared rings g^2 , g^4 , and g^6 , spring g^5 , and lock-nuts g^7 and g^8 , in combination with devices for imparting to the arbor F an oscillating movement from any of the moving members of the 105 engine, substantially as described.

11. In a lubricator, the inlet h^2 and discharge-orifice h^3 , communicating with each other by a channel filled with the reciprocating piston-rings j' and j'' , or their equivalents, 110 so as to cut off direct communication between the same, substantially as described.

12. In a lubricator, the parts for automechanically operating the feeding device, the same consisting of the oscillating arbor F , 115 fluted sleeve G , cams j' and j'' , grooved ring J , provided with a stop-pin, M , and bridge N , the tension device, split ring H , and inlet and discharge orifices h^2 and h^3 , all combined and operated substantially as described.
